POULTRY FEEDER TROUGH

Gerald L. Kitson, 9709 Belding Road,
Rockford, Mich. 49341

Continuation of design application Ser. No. 160,245, July
6, 1971, now Patent No. 229,030, dated Nov. 6, 1973.
This application Oct. 23, 1973, Ser. No. 408,373

Term of patent 14 years

Int. Cl. D30—03
U.S. Cl. D30—13

FIG. 1 is an end and top perspective view of a poultry feeder trough embodying my new design, with a portion broken away and omitted to indicate indeterminate length.

FIG. 2 is a top plan view of the poultry feeder trough shown in FIG. 1 having portions broken away and omitted to indicate indeterminate length.

FIG. 3 is an end elevation of the poultry feeder shown in FIGS. 1 and 2.

FIG. 4 is an isometric exploded exterior view of an end fragment of the poultry feeder trough shown in FIGS. 1, 2, and 3.

FIG. 5 is an isometric exploded interior view of the end fragment of the poultry feeder trough, showing the face of the end closure opposite of that visible in FIG. 4.

In FIG. 1 and FIG. 2 it is to be understood that the structure omitted intermediate the ends of the poultry feeder continues throughout the length of the feeder trough.

The dashed line showing of the combined feeder pipe and support is included to illustrate the environment of the poultry feeder trough.

This application is a continuation of my copending application Ser. No. 160,245, filed July 6, 1971, Pat. No. D. 229,030, Nov. 6, 1973, and entitled Poultry Feeder Pipe Support.

I claim:

The ornamental design for a poultry feeder trough, as shown and described.
